UNITED STATES PATENT OFFICE

91,465

DESIGN FOR A CABINET FOR CASH REGISTERS

James Douglas Lorenz, Dayton, Ohio

Application October 8, 1932. Serial No. 45,259

Term of patent 14 years

To all whom it may concern:

Be it known that I, JAMES DOUGLAS LORENZ, a citizen of the United States of America, residing at Dayton, in the county of Montgomery, State of Ohio, have invented a new, original, and ornamental Design for a Cabinet for Cash Registers, of which the following is a specification, reference being had to the accompanying drawings, forming part thereof.

Fig. 1 is a perspective view of a cabinet embodying the design;

Figs. 2, 3 and 4 show a front, side and rear ele-

vation respectively thereof, on reduced scale, the keys being omitted from the showing of Fig. 2 for purposes of simplicity in illustration.

The design is illustrated in the several views of the drawings, as embodied in a cabinet, having a base, side and back walls, and a front wall which has the keyboard set therein.

I claim:

The ornamental design for a cabinet for cash registers, substantially as shown and described.

JAMES DOUGLAS LORENZ.

CERTIFICATE OF CORRECTION.

Design No. 91,465.

February 6, 1934.

JAMES DOUGLAS LORENZ.

It is hereby certified that error appears in the printed specification of the above numbered patent requiring correction as follows: Second column, after line 7, insert the following paragraph:

The cabinet surfaces are discontinuous and have breaks, set-backs, offsets and panel effects to give an accentuated tapering appearance to the cabinet from the base toward the top. The several walls, the base and the keyboard are preferably of contrasting materials, finishes or colors.

And that the said Letters Patent should be read with this correction therein that the same may conform to the record of the case in the Patent Office.

Signed and sealed this 3rd day of April, A. D. 1934.

F. M. Hopkins
